UNITED STATES PATENT OFFICE

MARTIN NYSTROM, OF CHICAGO, ILLINOIS, ASSIGNOR TO THE BRUNSWICK-BALKE-COLLENDER COMPANY, OF CHICAGO, ILLINOIS, A CORPORATION OF DELAWARE

DESIGN FOR A COMBINED PHONOGRAPH AND RADIO RECEIVING SET CABINET OR SIMILAR ARTICLE

Application filed January 23, 1929. Serial No. 29,735. Term of patent 7 years.

To all whom it may concern:

Be it known that I, MARTIN NYSTROM, a citizen of the United States, residing at Chicago, in the county of Cook and State of Illinois, have invented a new, original, and ornamental Design for a Combined Phonograph and Radio Receiving Set Cabinet or Similar Article, of which the following is a specification, reference being had to the accompanying drawing, forming part hereof.

The figure is a perspective view of a com-

bined phonograph and radio receiving set cabinet, or similar article, embodying my invention.

I claim:

The ornamental design for a combined phonograph and radio receiving set cabinet, or similar article, substantially as shown.

In testimony whereof I hereunto subscribe my name.

MARTIN NYSTROM.
